Attorney

UNITED STATES PATENT OFFICE.

LOUIS W. GERHARDT, OF COATESVILLE, PENNSYLVANIA.

FURNACE PROTECTION.

Application filed August 14, 1922. Serial No. 581,635.

To all whom it may concern:

Be it known that I, LOUIS W. GERHARDT, a citizen of the United States, residing at Coatesville, in the county of Chester and State of Pennsylvania, have invented certain new and useful Improvements in Furnace Protection; and I do hereby declare the following to be a full, clear, and exact description of the invention, such as will enable others skilled in the art to which it 5 pertains to make and use the same.

My invention relates to means for protecting the walls, or what are sometimes known as bulk-heads of furnaces, with special reference to melting furnaces of the open hearth type, or heating furnaces constructed largely of refractory materials.

In operating furnaces of this character, and particularly those of the reversing type which are regenerative or recuperative, it is found that the heat of the outgoing gases is so great as to melt, fuse, flux or otherwise destroy the end walls or portions thereof, and this also causes irregularities in the shape of the flues and channels, which leads to incorrect introduction and mixtures of the gases, besides which the frequent destruction of these walls necessitates temporary shut-downs for repairs while the parts so destroyed are being replaced or rebuilt.

This destruction of the end walls of a furnace generally occurs at places opposite the ports or passages where the outgoing products of combustion impinge against the walls and are thereby deflected downwardly to the regenerators, recuperators, or stack flues. These portions as sometimes built are composed of a wall of silica brick about thirteen and one-half inches thick, but on account of the action of the intense heat of the outgoing products of combustion, these bricks or some of them are being continually fluxed or destroyed, so that such portions ordinarily last only a week or ten days, and at the end of this time new walls or portions are usually necessary, and in making such repairs, under the difficult conditions of heat, the cost of labor is excessive and the work cannot be done very well, which again leads to quick destruction of the walls when again put in use, for the reasons above stated. In addition to this such repairs delay the operation of the furnace and increase the cost of production.

Instead of this prior usual construction

I provide a hollow frame, which may be cooled by water or other fluids arranged to circulate therethrough, and within and around this frame I construct walls of refractory materials, preferably of different characters, each best adapted to suit the heat and conditions to which it is subjected.

My cooler is made in the shape of a frame somewhat similar to a door or window frame, but with a pair of side members, a bottom member, a top member and intermediate members, all of which are hollow and through which cooling fluid circulates, and my cooling frame is made in this shape in order that it may be adequate for the purpose and not of undue size, and by reason of the frame construction it provides ample cooling, whereas if such a structure were made in the shape of a box, too much cooling effect would be produced and in addition to which certain parts would be burned out or destroyed owing to the lack of circulation of cooling fluid, all of which is obviated by my construction.

My frame is provided with abutting and adjacent refractory material composed of brick walls of suitable kinds, some of which are built within the frame and others arranged surrounding and in contact with it.

My device in general consists of a hollow steel frame, which, generally speaking, resembles a door frame, provided with an arched or segmental top portion with the usual side jambs, base and lintel portions, and this frame may also be provided with one or more cross members connecting the jambs in order to strengthen the frame and at the same time assist in cooling the adjacent parts of the refractory materials. I may also provide within the frame a smaller frame which forms a portion thereof, and which is also water-cooled, and within this smaller frame refractory materials are set which may be easily removed to permit access to the port or flue which they are opposite, for the purpose of quick inspection and repair. This arrangement therefore allows for quick and rapid inspection and repair of the port by removing the smaller portion of the refractory material within the small opening in the frame, so that there is practically no delay in the operation of the furnace occasioned by this.

The water or other cooling fluid preferably enters the hollow frame at the bottom

and circulates upwardly throughout the various portions and is discharged from the top, and in such a way as to avoid producing an air or steam pocket.

- 5 The cross members of my frame as illustrated divide it into three panels, and each of the main panels contains a brick wall preferably made of standard nine-inch magnesite brick, the frame being of the same 10 depth as the length of the brick. The upper cross arm is provided with a small rectangular hollow frame, preferably formed integral and connecting with the other portions of the frame, having an opening of 15 approximately one square foot or so in size, which will exactly contain a number of standard first-class hard flint clay bricks, which can be removed as necessary without disturbing the other parts of the wall. 20 These brick may thus be frequently removed for examination and repair of the ports and flues adjacent this opening, and the use of these clay bricks reduce the cost of construction and saves loss and damage of 25 the other more permanent but expensive magnesite brick.

My frame is preferably constructed of a steel plate, which may be one-half inch or thereabouts in thickness and is made hollow by flanging three of the sides, while the fourth side, after being cut to shape, is welded in place with its edges contiguous to the other edges of the frame. In the bottom cross arm or base I preferably weld 30 two pipe sleeves, to one of which the inlet pipe is connected, while the other is provided with a valve for flushing or draining the same.

40 In the upper part of the frame, as illustrated, is an auxiliary frame within the main frame, in which is welded a pipe nipple, to which is secured an outlet pipe, and another nipple is welded in the top member, both connected together and to an outlet 45 pipe, and the water or other fluid discharged through them may be used for cooling other portions of the furnace coolers, or discharged as desired.

50 In order to easily handle the frame I provide two lugs welded to the top portion thereof, which are provided with holes in which lifting hooks, etc., may be inserted.

55 My frame may be placed in position when the furnace is first constructed, or when the furnace has been shut down for repairs, and the inner portion of the frame should be preferably seated flush with the inner surface of the gas uptake wall, and in order to allow for expansion a space should be left between the frame and the adjacent brickwork, and this space will be closed as the brickwork is expanded by the heat.

60 After the furnace is brought up to heat the joint may also be pointed up, if desired, 65 so as to be thoroughly sealed as necessary.

After the frame is in place the three main panels are preferably lined with magnesite brick and on the outside of the frame a wall of nine-inch silica brick is laid the entire width and height of the frame. The silica 70 brick panel is bonded to the magnesite lining on the bottom course of the middle magnesite panel, thus helping to hold the frame and walls in position.

I also prefer to provide expansion joints 75 of about a half inch on one side and the top of both the lower and middle panels, and a somewhat similar expansion joint around the upper panel of the brickwork.

I prefer to provide an opening in the 80 outer wall of silica brick to correspond with the small opening of the frame in order to allow ready access to the clay brick which are set within the opening. As these clay 85 brick do not expand very much they are easily removed and replaced.

I prefer to form the upper portion of the frame arched or segmental, and above the frame I construct a brick relief arch to support the end wall of the furnace over the 90 frame, which arch preferably extends only to the face of the lifting straps, the outer silica brick panel extending above this point up to the port arch so as to permit the removal of the frame without damage to 95 the relief arch.

As compared with prior constructions, I find by actual practice that the portion of the furnace construction in the neighborhood of my bulk-head frame will last six or 100 eight times as long as without it, with consequent economy and ease of operation.

Having thus given a general description of my invention, I will now, in order to make the matter more clear, refer to the annexed sheet of drawings, which forms part of this specification, and in which like characters refer to like parts:

Figure 1 is a vertical longitudinal sectional elevation through a portion of the end 110 of an open hearth furnace, illustrating the application of my invention, the section being taken on the line I—I of Figure 2; Figure 2 is an end elevation of the top portion of an open hearth furnace illustrating the 115 position of my improved water-cooled frame in the wall of the furnace; Figure 3 is a transverse sectional elevation through a portion of the upper end of the gas flue taken on the line III—III of Figure 1; Figure 4 120 is a vertical longitudinal sectional elevation of a portion of the top of the gas flue taken on the line IV—IV of Figure 3; Figure 5 is an elevation of my improved water-cooled frame, and Figure 6 is a vertical sectional 125 elevation through the frame taken on the line VI—VI of Figure 5.

Referring now to the characters of reference on the drawings:—1 represents the furnace hearth in general; 2 is the end wall of 130

the furnace composed of bricks or refractory material; 3 are the air flues, 4 is the gas flue, 5 is the gas port, 6 the air port, and 7 is the mixing chamber or the end portion of the furnace in which the gases and air are united on introduction. It will be understood that Figure 1 represents only one end of a furnace, and the other end may be of similar construction. 8 is the outer portion 10 of the wall adjacent to my water-cooled frame, which wall is preferably composed of silica brick; 9 is the water-cooled frame as a whole, which is hollow, as before stated, 15 being the side portions thereof, and 11 the horizontal portions uniting the same; 12 is the auxiliary frame connected with the upper horizontal member, and 13 is the upper curved or arched portion of the frame. Around the outer portion of the frame are 20 spaces or expansion joints 14, while 15 are the outlet pipes which are connected to the joint outlet pipe 16. The inlet pipe is one of the two pipes 17 at the bottom, one of 25 which may be connected to the supply of cooling fluid and the other may be provided with a valve for draining or flushing the frame. The lifting lugs 18 are welded to the upper portion of the frame and are provided with holes 19 therein in which lifting 30 hooks or other tools may be inserted. 20 is the magnesite brick wall within the panels of the frame, while the small opening for access to the gas port is 21, within which is constructed the smaller wall of clay brick 22.

35 Although I have shown and described my invention in considerable detail, I do not wish to be limited to the exact and specific details thereof as shown and described, but may use such modifications in, substitutions 40 for, or equivalents thereof as are embraced within the scope of my invention, or as pointed out in the claims.

Having thus described my invention, what I claim and desire to secure by Letters Patent is:—

1. The combination with a furnace, of a wall, subject to destructive heat, of a fluid-cooled frame, having a plurality of openings, mounted therein, comprising separate 50 but connected hollow side, top and bottom portions, with refractory materials surrounding and within the same.

2. The combination with a furnace, having an end wall subject to destructive heat, 55 of a hollow fluid-cooled frame mounted therein, comprising substantially straight side and bottom portions and an arched upper portion, refractory materials abutting the outer side of same with a relieving arch 60 above said upper portion and refractory material within said frame.

3. The combination with a furnace end wall, of a hollow fluid-cooled frame, having a plurality of openings, mounted therein 65 provided with separate but connected side,

bottom and top portions and intermediate hollow portions connecting said side portions.

4. The combination with a furnace end wall, of a hollow fluid-cooled frame, having 70 a plurality of openings, mounted therein provided with separate but connected side, bottom and top portions, and intermediate hollow portions connecting said side portions, and refractory material surrounding 75 and within said frame.

5. The combination with a furnace end wall, of a hollow fluid-cooled frame, having 80 a plurality of openings, mounted therein, comprising separate but connected top, side and bottom portions, and intermediate portions connected to said side portions, and another portion connected with one of said intermediate portions, enclosing an opening, bricks removably mounted in said opening and within and around the other portions of said frame.

6. The combination with the end wall of an open hearth furnace, of a fluid-cooled frame, having a plurality of openings, set 90 within the same at and near the location where outgoing gases contact, comprising separate but connected side portions, a bottom portion, an upper arched portion and an intermediate portion surrounding a repair opening, refractory materials mounted within and around said frame and within said repair opening, and means for supplying cooling fluid to and delivery of same 95 from said frame.

7. The combination with the end wall of an open hearth furnace, of a fluid-cooled frame, having a plurality of openings, set 105 within the same at and near the location where outgoing gases contact, comprising separate but connected side portions, a bottom portion, an upper arched portion and an intermediate portion surrounding a repair opening, refractory materials mounted within and around said frame and within 110 said repair opening, means for supplying cooling fluid to and delivery of the same from said frame, and a valve-controlled drain opening in the lower portion of said frame.

8. A water-cooled frame of the character described, comprising side members, a bottom member, an upper member of arch form, one or more intermediate members connecting said side members, one of said intermediate members being provided with members forming a smaller auxiliary opening within said frame, said frame being formed of pressed metal plate integrally welded together, and provided with inlet and outlet openings for the circulation of fluid therein.

9. A water-cooled frame of the character described, comprising side members, a bottom member, an upper member of arch form, one or more intermediate members connect-

ing said side members, one of said intermediate members being provided with members forming a smaller auxiliary opening within said frame, said frame being formed of pressed metal plate welded together, and provided with inlet and outlet openings for the circulation of fluid therein, magnesite brick within the main panels of said frame, and clay brick within the auxiliary opening thereof.

10. A water-cooled frame of the character described, comprising side members, a bottom member, an upper member of arch form, one or more intermediate members

connecting said side members, one of said intermediate members being provided with members forming a smaller auxiliary opening within said frame, said frame being formed of pressed metal plate welded together, and provided with inlet and outlet 20 openings for the circulation of fluid therein, magnesite brick within the main panels of said frame, clay brick within the auxiliary opening thereof, and an outer wall of silica brick adjacent said frame.

In witness whereof I hereunto affix my signature.

LOUIS W. GERHARDT.
